[57] CLAIM

The ornamental design for a VHF antenna, as shown and described.

DESCRIPTION

FIG. 1 is a front elevational view of a VHF antenna showing my new design;

FIG. 2 is a right side elevational view thereof, the opposite side being identical;

FIG. 3 is a top plan view thereof;

FIG. 4 is a bottom plan view thereof;

FIG. 5 is a rear elevational view thereof;

FIG. 6 is a right side, front perspective view thereof; and,

FIG. 7 is a right side, front perspective view thereof with the telescoping antennas fully extended.

The connecting ribbon cable is shown fragmentarily for ease of illustration.
